UNITED STATES PATENT OFFICE.

ERNEST B. CLEWORTH, OF ST. PAUL, MINNESOTA.

HEATER.

1,338,855.

Specification of Letters Patent.

Patented May 4, 1920.

Application filed April 19, 1919. Serial No. 291,207.

To all whom it may concern:

Be it known that I, ERNEST B. CLEWORTH, a citizen of the United States, residing at St. Paul, in the county of Ramsey and State 5 of Minnesota, have invented certain new and useful Improvements in Heaters; and I do hereby declare the following to be a full, clear, and exact description of the invention, such as will enable others skilled in the art 10 to which it appertains to make and use the same.

My invention relates to stoves and furnaces herein designated generically as heaters, and more particularly for those designed 15 for the burning of coal, and provides therein an auxiliary air intake tube of the type sometimes designated as over fire air conduits. These over fire air conduits have usually been arranged to deliver through 20 the fuel door but sometimes have been brought up through the body of burning coal.

My invention particularly improves this latter type of auxiliary air supply device.

25 The invention is illustrated in the accompanying drawings wherein like characters indicate like parts throughout the several views. Referring to the drawings,

Figure 1 is a vertical section with some 30 parts broken away, illustrating my invention as applied to a furnace of the hot water or steam heater type;

Fig. 2 is a plan view of the nozzle section of the auxiliary air intake tube;

35 Fig. 3 is a section on the line 3—3 of Fig. 2;

Fig. 4 is a front elevation of the said nozzle;

Fig. 5 is a front end elevation of the auxiliary air intake tube and the device for operating the deflector which is applied to the nozzle;

Fig. 6 is a plan view of the nozzle deflector;

45 Fig. 7 is a section on the line 7—7 of Fig. 6; and

Fig. 8 is a front elevation of the said deflector.

Of the parts of the heater, to wit, as 50 shown, the hot water heater or furnace, the numeral 9 indicates the shell or body thereof, the same having the usual fuel door passage 10 with fuel door 11. Just above the grate bars 12 the shell 9 is provided with the 55 customary clinker door opening 13 adapted to be closed by the customary door 14. The

numeral 15 indicates the ash pit door which will usually be equipped with the customary damper 16.

In Fig. 1, the dotted line *y* indicates the approximate fuel level. In accordance with my invention, I provide an approximately L-shaped auxiliary air intake tube 17, the horizontal portion of which overlies the grate bars 12 with its outer end projecting 60 into and nearly through the clinker door opening 13. The upright portion of this tube 17 extends to a point above the fuel level *y* and terminates in a socket 17^a in which the downturned end of an elbow-like 70 tubular nozzle 18 is swiveled for rotation on a vertical axis.

The tube 17 is preferably of cast iron and its lower rear wall is made very thick or flanged so as to prevent the tube from being 75 warped by it. In the back of its upper portion it is shown as provided with a supporting screw 19 that bears against the rear wall of the shell 9 and is adjustable to set the upright portion of the tube in a vertical 80 position spaced from the walls of the shell 9. Other suitable devices desired may be used to hold the tube 17 in position.

At its inwardly projected upper end, the nozzle 18 is provided with laterally projecting arms 20 to which a deflector blade 21 is pivoted at 22. The deflector blade 21, on its top has laterally spaced beveled lugs 23 that not only serve as weights, but perform a more important function, to wit, they deflect the air laterally and spread the same 85 above the deflector blade when the latter is lowered. Also, the blade 21 is formed with depending side flanges 21^a that are beveled at their lower edges (see Fig. 7) so that 90 they will lap and form close joints with the beveled upper edges of the arms 20. At its pivoted outer end, said deflector blade 21 is provided with a short depending arm 24 to which the upper end of a small wire 100 cable or chain 25 is attached. This cable 25 is extended down through the nozzle 17, having frictional contact with the inner wall thereof, and down through the upright portion of the tube 17 and is attached at its 105 lower end to a windlass rod 26, which rod, at its inner end, is pivoted in the elbow of the tube 17, and at its outer end is pivoted in a bar 27, the ends of which are attached to a latch ring 28 rigidly secured in the outer 110 end of the tube 17.

The windlass rod 26 is capable of both ro-

tation and a slight endwise movement and at its outer end it is provided with a latch lever 29, the end of which is engageable with any of several circumferentially spaced notches 28^a of said ring 28. A coiled spring 30 surrounds the rod 26, reacts against the bar 27 and against a collar 31 on said rod 26 and presses the said rod inward so as to normally maintain engagement between the lever 29 and the engaged notch of the latch ring 28.

10 As is evident, by rotation of the windlass shaft 26, acting through the cable 25, the nozzle deflector plate 21 may be adjusted on its pivot 22 and thereby set in any of several different positions and there secured by the latch lever 29.

15 In the extreme uppermost position of the deflector plate 21 shown in Fig. 1, all of the air drawn in through the air tube 17 and nozzle 18 will be deflected downward directly onto the fire. This is desirable in some conditions of the burning fuel, but in other conditions, it is advisable to deliver a portion of the air horizontally. Obviously, 20 when the deflector plate 21 is lowered, an opening will be afforded between the free edge of said blade and the upper portion of the nozzle 18 so that more or less air, depending on the adjustment of the deflecting plate, will pass directly downward. By the use of a poker, the nozzle portion of the auxiliary air intake device may be moved from one side to the other or set at the center 25 of the fire pot, as may be required to produce the best results. The air in passing through the tube 17 and nozzle 18, will of course, be preheated to a high degree so that it will very greatly increase the combustion as soon as it comes into contact with the burning fuel, and will thereby insure burning up of all of the gases and carbon so that there will be no resulting smoke from the combustion. Of course, for supplying 30 air to the air tube 17, either the clinker door must be opened or the damper which is usually provided therefor must be opened, but when it is desired to cut off this auxiliary supply of air the said door and its 35 damper may be closed.

40 What I claim is:

45 1. The combination with a heater, of an auxiliary air intake tube extended up through the fire pot thereof and provided at its upper end with a swiveled nozzle adapted to swing above the burning fuel, the said nozzle having a pivoted deflecting blade for regulating the downward deflection of the air above the fuel.

50 2. The combination with a heater, of an auxiliary air intake tube extended inward and thence upward through the fire pot thereof, a nozzle swiveled to the upper end

of said air tube and adapted to swing laterally above the fuel, and a deflector blade 65 pivoted to said nozzle.

3. The combination with a heater, of an auxiliary air intake tube extended inward and thence upward through the fire pot thereof, a nozzle swiveled to the upper end 70 of said air tube and adapted to swing laterally above the fuel, a deflector blade pivoted to said nozzle, and means for adjusting said deflector blade including connections extended downward through said 75 air tube.

4. The combination with a heater, of an auxiliary air intake tube extended inward and thence upward through the fire pot thereof, a nozzle swiveled to the upper end 80 of said air tube and adapted to swing laterally above the fuel, a deflector blade pivoted to said nozzle, and means for adjusting said deflector blade, a crank comprising a windlass shaft extended through 85 the inleading portion of said tube, and a cable attached to the inner end of said windlass shaft and extended upward and connected to said deflector blade.

5. The combination with a heater, of an auxiliary air intake tube extended inward and thence upward through the fire pot thereof, a nozzle swiveled to the upper end 90 of said air tube and adapted to swing laterally above the fuel, a deflector blade pivoted to said nozzle, and means for adjusting said deflector blade comprising a windlass shaft extended through the inleading portion of said tube, and a cable attached to the inner end of said windlass 95 shaft and extended upward and connected to said deflector blade, the said windlass shaft having a latch and being capable of limited endwise movement to operate said ratchet.

6. The combination with a heater, of an auxiliary air intake tube leading into the fire pot and having a nozzle located above the fuel, said nozzle having a pivoted deflecting blade, said deflecting blade having 100 a laterally beveled deflecting lug for spreading the air.

7. The combination with a heater, of an auxiliary air intake tube leading into the fire pot and having a nozzle located above 115 the fuel, said nozzle having a pivoted deflecting blade, the said deflecting blade on its upper surface having laterally spaced slightly beveled deflecting lugs for spreading the air.

120 In testimony whereof I affix my signature in presence of two witnesses.

ERNEST B. CLEWORTH.
